UNITED STATES PATENT OFFICE.

DAVID C. SHEELEY, OF WAYNESBOROUGH, PENNSYLVANIA, ASSIGNOR OF
ONE-HALF TO JACOB FRICK, OF SAME PLACE.

BABY-JUMPER.

SPECIFICATION forming part of Letters Patent No. 430,324, dated June 17, 1890.

Application filed March 1, 1890. Serial No. 342,289. (No model.)

To all whom it may concern:

Be it known that I, DAVID C. SHEELEY, a citizen of the United States, residing at Waynesborough, in the county of Franklin 5 and State of Pennsylvania, have invented certain new and useful Improvements in Baby-Jumpers; and I do hereby declare the following to be a full, clear, and exact description of the invention, such as will enable others skilled in the art to which it appertains to make and use the same.

My invention is an improvement in baby-jumpers; and it consists in certain novel features of construction and arrangement of 15 parts, which are hereinafter fully described and claimed.

I have illustrated one form in which I have contemplated embodying my invention in the accompanying drawings, in which—
20 Figure 1 is a perspective view of my improved baby-jumper, the supporting-cords being broken away. Fig. 2 is a longitudinal section of the same, the parts being extended into a horizontal plane. Figs. 3, 4, and 5 are 25 detail views of parts of the construction.

The frame of my improved baby-jumper consists of a seat portion and a back portion pivotally connected together and adapted to be adjusted with respect to each other. The 30 seat portion consists of the side pieces A A, connected together at their forward extremities by the cross-bar a. The side pieces B B of the back portion are pivotally connected to the pieces A A at b b, and the said pieces 35 B B are connected together at their free ends by the cross-bar b'. The side pieces B are each provided with a segmental portion b², which overlaps the adjacent side piece A when the device is in the position shown in 40 Fig. 1, arranged in the form of a chair. The curved edges of the portions b² are concentric with the point of pivoting b, and the side pieces A A are provided with guides a' a', secured thereto, which engage the said segmental portions and guide them when the 45 parts are moved with respect to each other and prevent them from springing apart. The parts B B are also provided with pins or straps b³ b⁴, which are so placed as to engage 50 the guides a' a' and limit the backward movement of the back portion.

In order to adjust the parts with respect to each other to allow the back to be tilted rearwardly and extended into the plane of the seat portion when the device is desired 55 to be used as a bed, I provide the side pieces A A with one or more holes or recesses a³ a², arranged concentrically with the point of pivoting b, and provide the parts B B with spring-actuated pawls or bolts b⁴ b⁴, adapted to engage the same. The pawls b⁴ b⁴ are mounted 60 in sockets b⁵ b⁵ and provided with springs b⁶ in any preferred manner, which tend to hold the said pawls in engagement with the side piece B. By this means the pawls may be 65 drawn out and the parts adjusted to the desired position, where they will be held by the engagement of the pawls with the proper holes or recesses. The side pieces A A are also preferably provided with segmental portions a³, 70 which conform to the shape of the overlapping segmental portions b² of the side pieces B B when the parts are arranged as a bed, as best seen in Fig. 2.

In pivoting the side pieces A and B together I prefer to employ the construction shown in Fig. 4. This construction consists of the face-plate b⁷, having a downwardly-extending hook portion b⁸. This plate is also provided with the pivot b⁹, which passes 80 through the parts A and B and engages a plate or washer b¹⁰ on the outside of the frame. These parts are secured together by riveting, as shown, or by any other preferred means, such as a screw or nut. The plate b⁷ is also 85 provided with a rearwardly-extending arm b¹¹. The bottom and back of the device are preferably formed from a continuous piece of flexible material C, which is secured at each end to the cross-bars a and b', as shown 90 in Fig. 2. The material C is secured at opposite edges to the retaining projections b¹¹, adjacent to the point of pivoting b, by means of a rivet, screw, or other preferred means. By this construction I dispense with a central 95 cross-bar and yet secure the flexible material from being drawn away from the sides of the frame, and also provide an intermediate support for the said material. I also provide the device with a foot-rest, as shown in Fig. 2. 100 This consists of the frame D formed, preferably, of stiff wire suitably covered with flexi-

ble material, and provided at its free ends with the slotted yokes d , which engage the cross-bar a . The yokes d are also provided each with a hook or projection d' , adapted to engage one or more pins $d^2 d^3$ on a plate d^4 , secured to the side piece A. When it is desired to have the foot-rest form a continuation of the seat portion, the hook d' is made to engage the pin or lug d^2 , as shown in Fig. 2, and this will customarily be the manner of using the foot-rest. When the device is extended to form a bed, frame D is desired to serve as a rest, and when the parts are arranged as a chair the hooks d' are made to engage the pins d^3 , and the foot-rest will then occupy an inclined position, as shown in dotted lines, Fig. 1. When not in use, the foot-rest will be disengaged from the pins $d^2 d^3$, folded beneath the seat portion, and placed in engagement with the hooks b^8 of the hinge-casting, as shown in Figs. 2 and 4. The slotted yokes d will allow for the longitudinal movement of the frame D in changing its positions without becoming disengaged from the cross-bar a .

25 The jumper-frame, hereinbefore described, is supported from some suitable point by means of cords or ropes $e e'$, secured to the free ends of the seat portion and to the free end of the back portion, each cord extending from one point to the other, as clearly shown in Fig. 2. These cords engage a friction-block E, which consists of wood or other suitable material, provided with four parallel passages, and each cord passes upward through one passage and down through another, the edges of the apertures adjacent to their upper extremities being smoothed to prevent wear of the cords. The block E is also provided with a swivel-hook E' for supporting the same and allowing the device to be rotated, if desired, on the said swivel. When the block is suspended to some rigid support, it will be seen that the frame of the jumper can be instantly placed in any desired position, the cords sliding through the apertures in the block to permit the said adjustment, and when properly adjusted the cords will be held by frictional engagement from being moved in any way by the movement of the frame or the occupant. I also provide the cords $e e'$ with a stop to engage the said block and limit the movement of the jumper, as desired. I have found by experience that there is no necessity for a stop to limit the backward movement of the cords; but I provide the cords in rear of the block with a stop to limit their forward movement and prevent the occupant from being accidentally thrown

out forward by carelessness in adjusting the position of the frame. This stop consists of a coupling e^2 , which connects the cords $e e'$ at that point, and is so constructed as to engage the under face of the block as the cords are drawn through the same and limit the movement of the cords, as described. By attaching the said stop to both cords I force the cords to move together and evenly, thereby avoiding any uneven adjustment and consequent twisting of the frame by having one side higher at one end than the opposite side.

What I claim, and desire to secure by Letters Patent, is—

1. A baby-jumper consisting of a seat and a back portion hinged or pivoted together, cords extending from the free end of the seat portion to the free end of the back portion, and a supporting device frictionally engaging said cords intermediate their ends, substantially as described. 75

2. The combination, with a baby-jumper consisting of a seat and a back portion hinged together, of cords extending from the free end of the seat portion to the free end of the back portion, a supporting device frictionally engaging said cords intermediate their ends, and a stop secured to said cords, substantially as described. 80

3. A baby-jumper consisting of a seat and a back portion pivoted together, said parts having overlapping curved portions concentric with the point of pivoting, a guiding device upon one of said curved portions and engaging the other, a spring retaining-bolt, and supporting means connected to the free ends of the seat and back portions, substantially 95 as described.

4. A baby-jumper consisting of a seat and a back portion pivoted together, the said seat and back being composed of frames consisting of side pieces joined by a cross-bar at their free ends, the two frames being pivoted together by short pivots connecting the side pieces of the frames, flexible material extending from the cross-bar of one frame to that of the other and attached to the frames in line with the pivots, a device for retaining the frames at the desired angle of adjustment in relation to each other, and supporting means connected to the free ends of the seat and back, substantially as described. 100 105 110

In testimony whereof I affix my signature in presence of two witnesses.

DAVID C. SHEELEY.
